United States Patent Office

Des. 181,305
Patented Oct. 29, 1957

181,305

DESK TRAY OR THE LIKE

Lawrence C. Martino, Girard, Ohio

Application May 6, 1957, Serial No. 46,033

Term of patent 14 years

(Cl. D74—1)

Fig. 1 is a front perspective view of a desk tray showing my new design;

Fig. 2 is a front elevational view;

Fig. 3 is an end elevational view; and

Fig. 4 is a rear elevational view thereof.

The broken line showing of a calendar in Fig. 1 is for illustrative purposes only.

I claim:

The ornamental design for a desk tray or the like, as shown and described.
